FASTENER ATTACHING MEMBER AND FASTENER INSTALLATION

**Scipione M. Del Camp, Maywood, Ill., assignor
to Cinch Manufacturing Corporation, Chicago,
Ill., a corporation of Illinois**

Application May 3, 1939, Serial No. 271,618

3 Claims. (Cl. 248—223)

This invention relates to improvements in fastener installations and relates particularly to an improved attaching means for securing a unit of manufacture to a supporting panel.

One of the objects of my invention is the provision of an attaching means for securing firmly a unit to supporting panels having varying thicknesses.

10 Another object relates to an improved attaching means constructed in a way to space the unit from the supporting panel when the parts of the installation are completely assembled.

Other objects and features of my invention will be apparent from inspection of the drawing and specification hereinbelow set forth.

Referring to the drawing, in which I have illustrated a preferred embodiment of my invention:

Fig. 1 is a front plan view of an electrical installation embodying my invention;

Fig. 2 is a bottom plan view of the installation shown in Fig. 1;

Fig. 3 is a sectional view taken along the line 3-3 of Fig. 2 with the lower supporting panel omitted;

Fig. 4 is a front view of an electrical unit embodying my invention before attachment thereof to a support;

Fig. 6 is a front view of the attaching member shown in Fig. 5.

Fig. 7 is a side elevation of a soldering lug which may be used in assembly with the electrical unit;

Fig. 8 is a rear plan view of the lug installation shown in Fig. 7;

Fig. 9 is a bottom plan view of the lug with the lead wires omitted; and

Fig. 10 is a bottom view of the installation shown in Figs. 7 and 8.

trated in Figs. 1-3, I have shown an electrical
45 unit such as a condenser can 1 secured in spaced
relation to a support such as a mounting plate
2 by means of an attaching member 3 assembled
with the condenser can adjacent its lower end
and providing a plurality of projecting portions
50 4 extending beyond the lower end of the can
and through the plate 2 and providing means en-
gaging the rear face 5 thereof (Fig. 3). The
mounting plate 2, which may be of metal or
plastic material, has a central opening 6 and a
55 plurality of narrow openings 7 disposed around

the opening 6 for receiving the projecting portions 4. The mounting plate 2 is in turn secured to a panel 8, which may be a part of a radio set, by any suitable means such as the rivets 9. The panel 8 has an opening 10 in alignment with the opening 6. Soldering terminals 11, adapted to be electrically connected with the condenser body (not shown) by suitable connecting leads (not shown), extend from the lower end of the condenser can 1 through the opening 6 of the mounting plate and the opening 10 of the support 8. The condenser can 1 has a peripheral flange 12 adjacent its lower end within which are maintained a pair of insulating plates 13 and 14 (Fig. 2).

The soldering terminals 11 form no part of my present invention as the specific construction of the same is embodied in the invention of another person who has filed an application on the same. The terminals have been illustrated and described herein merely incidentally to a detailed description of the type of electrical unit with which my improved mounting means is preferably used. 20

Referring in detail to the attaching member 3, I have shown one preferably formed of one piece of sheet metal having a flat ring-like base 15 adapted to be disposed within the flange 12 of the condenser can 1 and clenched between the lowermost insulating plate 14 and inwardly-turned edges 16 of the flange (Fig. 3) so as to maintain the attaching member in assembly with the condenser can. The projecting portions 4 extend from inner edges of the base 1 in substantially perpendicular relation to the plane of the base. Each of the projecting portions 4 is of flat construction and provides a spacing portion 17 adjacent the base 15. The spacing portion 17 has opposed support-engaging edges 18 converging toward their ends away from the base 15 and spaced apart at predetermined points thereon a distance which is greater than the length of the openings 7 with the result that the edges or shoulders 18 engage the upper surface 19 of the mounting plate to space the condenser can from the plate. Each of the projections 4 has a twistable portion 20 forming an extension of the spacing portion 17 and adapted to project through an opening 7 of the mounting plate. Each of the twistable portions 20 has a pair of elongated support-engaging elements or lugs 21 integral with opposed sides of the projecting portion and disposed normally in the plane of the projecting portion. Each of the lugs 21 has one end integrally joined to the twistable portion 20 and the other end integrally joined to the flange 12 of the condenser can 1.

20 and its opposite end free and in normal position in adjacent relation to the spacing portion 17.

- 5 Attachment of the condenser can 1 to the mounting plate 2 is quickly and easily accomplished by moving the projecting portions 4 through the apertures 7 until the shoulders 18 engage the upper surface 19 of the mounting plate adjacent the apertures 7. Next the portions 20 of the projecting portions 4 extending beyond the rear face 5 of the mounting plate are twisted by a suitable tool (not shown) to move the lugs 21 out of the normal plane of the projecting portions to engage tightly behind the surface 5. 10 One of the features of my invention is embodied in the particular dimensions of portions of the attaching member wherein the normal length of the lugs 21 is greater than the distance between the points of junction of the lugs with the portions 20 and the rear face 5 of the mounting plate when the projections 4 extend through the openings 7 and before twisting. As a result of these relative dimensions of the parts, the lugs are bowed after twisting of the portions 20 so 15 as to take up variations in thickness of the mounting plate 3 and at the same time draw the condenser can tightly against the mounting plate 2.

The soldering terminals 11 have a relatively straight flat body portion 22. Attaching means in the form of a flange or foot portion 23 integrally joined to one end of the body portion extends in right-angular relation to the normal plane of the body portion. The foot portion 22 is adapted to be held between the insulating plates 13 and 14, as most clearly shown in Fig. 3, so as to maintain the terminal in assembly with the condenser can and in upright position. A pair of spaced wing portions 24 integrally joined 20 to opposed side edges of the body portion extend out of the normal plane of the body portion. The wing portions 24 are adapted to be bent to embrace a connecting lead (not shown) between the foil of the condenser and the soldering terminal prior to soldering the connecting lead permanently to the body of the terminal. The connecting leads are adapted to extend from the foil of the condenser through openings (not shown) in the insulating plates 13 and 14 into 25 said soldered engagement with the terminals 11. Integral with the opposite end of the body portion 22 from the foot portion 23 I have provided an outwardly-extending wire-supporting means or lip portion 25. The lip portion extends beyond one side of the body portion 22 and has a lower open face 26 adapted to support the bare wires 27 of the leads 28 (Fig. 7) so that the bare wires may be soldered thereto.

Although I have set out the preferred use of 30 my improved attaching member in connection with an electrolytic condenser, it is understood that the part may be used in combination with units of manufacture of other shapes and forms. Furthermore, I perceive that projecting portions 35 embodying one or more features of my present invention might be formed integrally with the

lower end of the condenser can 1 so as to effect a satisfactory attaching means for securing the unit to a panel.

Although I have illustrated and described a preferred embodiment of my invention, I do not wish to be limited thereby because the scope of my invention is best set out in the following claims.

I claim:

1. In combination, a support, a part to be secured to said support and attaching means for securing said part to said support, said attaching means comprising projecting portions extending beyond the outermost margins of an end of said part, each of said projecting portions passing through an opening in said support and having integral lug-shaped support-engaging elements adjacent its opposite edges and normally in the plane of said projection, said elements having free end portions facing said end of said part and spaced therefrom, and said projections being twisted on the opposite side of said support from said part to dispose said support-engaging elements behind said support. 1

2. In combination, a support, a part to be secured to said support and an attaching member for said part, said attaching member comprising a base portion secured adjacent an end of said part and projecting portions extending from said base portion beyond the outermost margins of 30 said end, each of said projecting portions having a twistable portion passing through an opening in said support to a position beyond the lower surface thereof and having integral lug-shaped support-engaging elements adjacent its opposite edges and normally in the plane of said projection, said elements being joined at one end to said twistable portion and having a free end at its opposite end facing said base and spaced therefrom, the length of said support-engaging 35 elements being greater than the distance between the points of junction of said elements with said twistable portion and said lower surface of said support, and said twistable portions being twisted to dispose said support-engaging elements behind said support, and said elements being bowed by said twisting action. 40

3. In combination, a support, a part to be secured to said support and attaching means for securing said part to said support, said attaching 50 means including a projecting portion extending beyond outermost margins of an end of said part, said projecting portion passing through an opening in said support and having an integral bendable lug-shaped support-engaging element adjacent one edge and normally in the plane of 55 said projection, said element having a free end portion facing said end of said part and spaced therefrom, and said projection being twisted on the opposite side of said support from said part to dispose said support-engaging element behind said support whereby the said element may adjust itself to the thickness of said support by bending relative to the rest of said projection. 60
